UNITED STATES PATENT OFFICE

2,616,356

HEATING AND VENTILATING APPARATUS

George B. Cunningham, Birmingham, Ala., assignor to Cunningham Engineering Company, a partnership

Application April 13, 1949, Serial No. 87,330

6 Claims. (Cl. 98—116)

1

This invention relates to combined ventilating and heating apparatus adapted for installation in the wall or ceiling of a room and has for an object the provision of apparatus of the character designated which shall include a heating unit and a reversible fan and in which the heating unit is so located that it offers no interference to the flow of air when the apparatus is being used as a ventilating unit.

A further object of my invention is to provide a combined heating and ventilating apparatus which shall include a heating unit and a reversible fan, together with improved means for directing the flow of air induced by the fan over the heating unit when the apparatus is being used for heating.

Another object of my invention is to provide a combined heating and ventilating apparatus which shall include a reversible fan mounted in a suitable opening in a room, together with shutters for closing the opening, and automatic means for closing the shutters when the apparatus is not in operation and when operating to heat the room.

Among other important features, my invention provides improved heating and ventilating apparatus including a reversible fan, a housing for the fan and shutters for the housing, together with a heating unit positioned at one side of the housing, all constructed and arranged whereby, when the apparatus is being used for ventilating, the shutters are open and the air current induced by the fan flows without restriction to one side of the heating unit, and when the apparatus is used for heating, the shutters are closed and the reverse air current is directed over the heating unit.

Apparatus embodying features of my invention is illustrated in the accompanying drawings, forming a part of this application, in which:

Fig. 1 is a top plan view of apparatus constructed in accordance with my invention mounted in an opening in a room;

Fig. 2 is a sectional view taken along the line II—II of Fig. 1;

Fig. 3 is a detail sectional view drawn to a larger scale and taken along the line III—III of Fig. 1 to show the shutter operating means;

Fig. 4 is a bottom plan view of the apparatus showing the shutters in closed position and with parts broken away;

Fig. 5 is a detail sectional view showing the manner in which the shutters are mounted in the frame;

Fig. 6 is a sectional view taken along the line VI—VI of Fig. 5;

Fig. 7 is a detail bottom plan view showing a modified means for operating the shutters;

Fig. 8 is a detail sectional view taken along the line VIII—VIII of Fig. 7;

2

Fig. 9 is an enlarged detail view of a part of the shutter operating mechanism, and

Fig. 10 is a detail sectional view, drawn to an enlarged scale, of the heating unit.

Referring now to the drawings for a better understanding of my invention, I show a generally rectangular frame 10 adapted for mounting in an opening of the ceiling or wall of a room or other enclosure and through which my improved apparatus withdraws air for the purpose of ventilation, and introduces a current of heated air for heating. As shown, the rectangular frame 10 may conveniently be made of wood. Secured to the frame 10 in any suitable manner, along the sides thereof, is a rectangular metal frame made up of angles 11 with their flanges 12 turned inwardly of the frame 10. Mounted in the frame 11 are a plurality of shutters 13 each of which is made of metal with one edge rolled over, as shown at 14, around a rod 16, which is journaled in holes provided in the upstanding flange 12 of the frame 11, as shown in Fig. 5 of the drawing. The ends of the rod 16 may be provided with bosses 17 to prevent the rods from coming out of the holes in which they are mounted. The opposite edge of each of the shutters 13 is curved over as shown at 18 in Figs. 3 and 6, and the shutters are of such width, that the curved portion 18 fits over the turned over portion 14 of its adjacent shutter when the shutters are in closed position as shown in Fig. 3 of the drawing. Preferably also, each of the shutters 13 is provided with a strip of felt 19 adjacent its turned over portion 14 so that, when the shutters are closed, as presently to be described, the noise of closing is deadened.

Each of the shutters 13 is provided with a clip 21 suitably secured thereto as at 22, which clips are all pivotally connected to an operating rod 23 by means of pins 24. Connected to the rod 23 is a link 26, and connected to the link 26 is a second operating arm 27. A spring 28 is connected to the arm 27 at 29 and is anchored at its opposite end 31 to the casing, whereby the shutters are always biased toward a closed position. In order to cushion movements of the operating arm 27, it is connected to the link 26 by means of a pin 32, see Fig. 9, extending through a slot 33 in the outer end 35 of the link 26 and which bears against a spring 34. The lower end of the spring 34 bears against an abutment 36 which surrounds the link 26. The link 26 is made adjustable as to length by having its outer end 35 screwed into the inner end as shown in Fig. 9 and held in adjusted position by means of a nut 40. The arm 27 is actuated in a direction to open the shutters 13 by means of an electric motor 37, the operation of which will be described hereinafter.

It will be noted by reference to Figs. 2 and 4

of the drawings that the shutters 13 do not control the entire area of the opening defined by the frame 10. In one side of the opening, is mounted an electric heating unit 38 comprised of a plurality of heating elements 39 and 41 which are provided with heat radiating fins 42. The heating unit is provided with a casing comprised of side members 43 and 44, the member 43 being curved upwardly and over to define a lateral opening 46 which may be covered by a screen 47. Preferably, also, the side member 43 is lined with insulating material, such as fiber glass, as indicated at 45. As shown in Figs. 2 and 4, the heating unit 38 is secured at its ends, as shown at 43 and 49, to the flange 12 of the frame 11, and along one side bears against the frame 11.

Mounted on the frame 10 on the opposite side from the metal frame 11, is a fan housing 51 which is frusto-conical, or funnel-like, in shape with its axis eccentrically located with respect to the center of the frame 10, whereby to provide a covered recess 52 at one side of the frame for the heating unit 38. As shown in Fig. 2, the housing 51 is provided with a substantially flat portion 53 which extends over the recess 52.

Extending across the housing 51 and secured thereto near the inner end thereof are a pair of angle braces 54 and 56. Mounted on the braces 54 and 56 is a fan 57, having a shaft 58 mounted in a bearing 59 which, in turn, is supported from angle supports 54 and 56 by means of a plate 62. The shaft 58 extends through the bearing 59 and has mounted on its opposite end a pulley 63 which is driven by means of a reversible electric motor 64 and belt 66. As shown in Fig. 2 of the drawing, the fan 57 is mounted with a substantial portion of its blades located within the housing 51 so that, when the fan is operating in a direction to blow air into the room, and with the shutters 13 closed, an air current is forced into the housing, against the closed shutters, and into the recess 52 in which the heating element 38 is located. In this way, all of the air current induced by the fan 57 is forced to flow over and through the heating element. On the contrary, when the fan is rotating in the opposite direction, to withdraw air from the room through the open shutters 13, the heating element itself and the cover 53 over the recess in which it is located, interrupt the flow of air thereover and all of the air current induced by the fan passes through the shutters 13 without restriction.

At 67 is shown a source of electric current. The reversible motor 64 is energized to run in one direction through a circuit 68 and to turn in the opposite direction through a circuit 69. A four-pole electric switch 71 is interposed in said circuits and when turned in one direction energizes the circuit 68 and when turned in the opposite direction it energizes the circuit 69. It will be understood that when the fan 57 is operating in a direction to draw air through the open shutters 13, the apparatus is used for ventilating and when operating in a direction to force air over and through the heating element 38, with the shutters 13 closed, the apparatus is used for heating. The heating element 38 is energized by means of an electric circuit 72 and the motor which operates the shutters 13 is energized by means of an electric circuit 73. A four-pole electric switch 74 is interposed in said circuits so that when the heating circuit 72 is energized, the circuit to the motor 37 is open, or deenergized, and the shutters 13 are closed

by action of the spring 28. When the switch 74 is turned in the opposite direction, to energize the circuit 73 and open the shutters 13, the circuit 72 to the heating element 38 is deenergized.

Instead of the electrical means heretofore described for operating the shutters 13, I may employ the mechanical means shown in Figs. 7 and 8. In accordance with this modification of my invention, I may employ a bell crank lever 76, which is pivotally mounted at 77 on the angle brace 54. Mounted on the outer end of the fan shaft 58 is a disc 78. One arm 79 of the bell crank lever is provided with a friction shoe 81 which bears against the disc 78, and which is pressed toward the disc by means of a pair of springs 82 and 83, which bear at their outer ends against a crosspiece 84 mounted on the arm 79. Preferably, the friction shoe 81 is provided with a V groove 86 therein which bears against a complementary edge 87 on the disc 78. The other arm 80 of the bell crank lever 76 is connected to a link 88 which, in turn, is connected to the operating rod 23 for the shutters 13. As shown in Fig. 7, the rod 88 passes through a hole in the outer end of the arm 76 and bears on its opposite sides against springs 89 and 90 to cushion its movements and deaden the sound of the opening and closing of the shutters.

It will be seen from a consideration of Fig. 7 of the drawing, that with the disc 78 rotating in the direction indicated by the arrow, the friction shoe 81 will remain in the full line position shown, in which position the shutters are open. If we assume the disc 78 to be rotating in the opposite direction, the shoe 81 will be pulled to the dotted position indicated in Fig. 7, in which position the arm 76 will have forced the shutters closed through the rod 23 and link 88. In event the fan is not in operation, the shutters are closed by means of a spring 91 secured at one end to the arm 76 and at its opposite end to a stationary member, not shown.

From the foregoing, it will be apparent that I have devised an improved heating and ventilating apparatus which is simple of design, economical of manufacture, quiet in operation, and one capable of operating efficiently either as a heating or cooling apparatus.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are specifically set forth in the appended claims.

What I claim is:

1. A combined heating and ventilating apparatus adapted for mounting in an opening in a room comprising a frame, a frusto-conical housing mounted on a frame and open at both ends, a reversible fan mounted in the housing substantially coaxial therewith, means to rotate the fan to induce a current of air through the housing into the room when used for heating and to exhaust air from the room when used for ventilating, a plurality of shutters pivotally mounted in the frame in position when open to afford free passage for the air current there-through from the room and to interrupt said passage when closed, a heating unit mounted in the frame at one side of the housing in position for the current of air induced by the fan to be deflected thereover by the shutters when

the shutters are closed, and means to close the shutters when the fan is being operated to blow air into the room and to open the shutters when the fan is being operated to exhaust air from the room.

2. A combined heating and ventilating apparatus adapted for mounting in an opening in a room comprising a frame, a frusto-conical housing mounted on the frame and open at both ends, a reversible fan mounted in the housing substantially coaxial therewith, means to rotate the fan to induce a current of air through the housing into the room when used for heating and to exhaust air from the room when used for ventilating, a plurality of shutters pivotally mounted in the frame in position when open to afford free passage for the air current therethrough from the room and to interrupt said passage when closed, a heating unit mounted in the frame at one side of the housing in position for the current of air induced by the fan to be deflected thereover by the shutters when the shutters are closed, and means constructed and arranged to open the shutters when the fan is operating to withdraw air from the room and to close the shutters when the fan is operating to blow air into the room, the opening through the housing being eccentrically located with respect to the center of the frame, thereby providing a covered portion under which the heating unit is located, and the fan blades being located within the housing opening thereby to direct the current of air over and through the heating unit into the room when the fan is operating to blow air into the room and the shutters are closed.

3. In a combined heating and ventilating apparatus adapted for mounting in an opening in a room, a frame surrounding the opening, a covered recess along one side of the frame, a funnel-like housing mounted on the frame laterally of the recess and having an opening therethrough eccentrically located with respect to the center of the frame, a heating unit located in said recess, a plurality of shutters mounted in the frame in position when closed to interrupt the passage of air through the frame and deflect the same over and through the heating unit into the room and when open to afford free passage of air therethrough from the room, a fan mounted in the housing with its axis of rotation substantially coaxial with the opening through the housing, means to drive the fan in a direction to force air into the room when the apparatus is used for heating and to drive the fan in a direction to withdraw air from the room when the apparatus is used for ventilating, and means to open the shutters when the fan is operating in a direction to withdraw air from the room and to close the shutters when the fan is operating to blow air into the room.

4. In a combined heating and ventilating apparatus adapted for mounting in an opening in a room, a frame surrounding the opening, a covered recess mounted in the frame along one side thereof, a heating unit in said recess, a funnel-like housing mounted on the frame laterally of the recess and having an opening therethrough eccentrically located with respect to the center of the frame, a plurality of shutters mounted in the frame in position when closed to interrupt the passage of air through the frame and deflect the same over and through the heating unit into the room and when open to afford free passage of air therethrough from the room, a fan mounted in the housing with its axis of rotation

substantially coaxial with the opening through the housing, means to rotate the fan selectively in a direction to force air into the room when the apparatus is used for heating and in a direction to withdraw air from the room when the apparatus is used for ventilating, means to open the shutters when withdrawing air from the room, and spring means operatively connected to the shutters to close them when the fan is not in operation and when operating to blow air into the room.

5. In a combined heating and ventilating apparatus adapted for mounting in an opening in a room, a frame surrounding the opening, a funnel-like housing mounted on the frame with the opening through the housing eccentrically located with respect to the center of the frame thereby providing a covered recess along one side of the frame, a heating unit located in said recess, a plurality of shutters mounted in the frame in position when closed to interrupt the passage of air through the frame and deflect the same over and through the heating unit into the room and when open to afford free passage of air therethrough from the room, a fan mounted in the housing with its axis of rotation substantially coaxial with the opening through the housing, a reversible electric motor operatively connected to the fan, an electric circuit connected to the reversible motor for operating the reversible motor in a direction for the fan to withdraw air from the room, a second circuit connected to said reversible motor for operating the reversible motor in a direction for the fan to force air into the room, a reversing switch interposed in the first and second mentioned circuits, a second motor operatively connected to the shutters for opening the shutters when withdrawing air from the room, a circuit connected to said second motor, and spring means operatively connected to the shutters to close them when the circuit to the second mentioned motor is deenergized.

6. In a combined heating and ventilating apparatus adapted for mounting in an opening in a room, a frame in the opening, a covered recess along one side of the frame, a heating unit in said recess, a funnel-like housing mounted on the frame laterally of the recess and having an opening therethrough eccentrically located with respect to the center of the frame, a plurality of shutters mounted in the frame in position when closed to interrupt the passage of air through the frame and deflect the same over and through the heating unit into the room and when open to afford free passage of air therethrough from the room, a fan mounted in the housing with its axis of rotation substantially coaxial with the opening through the housing, a fan shaft, means for driving the fan selectively in a direction to force air into the room when the apparatus is used for heating and in a direction to withdraw air from the room when the apparatus is used for ventilating, a lever arm operatively connected to the shutters to open and close them, and friction clutch means operatively connected to the lever arm to open the shutters when the fan is rotating in a direction to withdraw air from the room and to close the shutters when the fan is operating in the reverse direction.
